UNITED STATES PATENT OFFICE.

JONAS B. OSBORNE, OF DAGGETT, CALIFORNIA.

SELF-PROPELLING WAGON-TRAIN.

SPECIFICATION forming part of Letters Patent No. 352,346, dated November 9, 1886.

Application filed July 22, 1886. Serial No. 202,803. (No model.)

To all whom it may concern:

Be it known that I, JONAS B. OSBORNE, of Daggett, in the county of San Bernardino and State of California, have invented an Improvement in Self-Propelling Wagon-Trains; and I hereby declare the following to be a full, clear, and exact description thereof.

My invention relates to the class of wagon-trains, and more especially to those which are self-propelling.

My invention consists in a wagon-train, each member of which is provided with its own propelling mechanism, while one is provided with the means for generating the motive force or power, said force or power being transmitted through suitable connecting mechanism to the propelling machinery of each member, whereby each effects its own progression, and does not depend upon the tractile power of the others, all of which I shall hereinafter fully describe.

The difficulties of transportation where railroad privileges are denied have led to the formation of wagon-trains drawn by traction-engines or road-locomotives. These, while comparatively successful over good and well-defined hard roads, prove complete failures in desert countries, where the roads are sandy and soft. This is due to the fact that much of the tractile power of the locomotive is lost because its great weight and the resistance of the train causes it to sink deep in the sand, which impedes its progress.

The object of my invention is to overcome this difficulty by removing from any one member of the train the work of pulling the others and give to each its own traction merely, furnishing from the leading member the motive power only, and no tractile power whatever. In other words, instead of concentrating the tractile power in a single member of the train, I propose to divide it proportionately among all the members, giving to the leading member the work of generating the original power, but no pulling or drawing obligation.

I do not mean particularly to directly economize the original power, for I well know that a given force must be expended to move a given weight; but my purpose is to change the application of the power from a single member to all, so that no one member in the exercise of its power is liable by reason of undue

traction to sink in a soft or sandy road, and the whole train is therefore better adapted for such a road:

Referring to the accompanying drawings, Figure 1 is a side elevation of my wagon train. Fig. 2 is a bottom view of two of the wagons.

The train is composed of the leading member A and the following members B C D, respectively. These may all be any suitable form of wheeled vehicle, though I find that the simple two-wheeled trucks here shown are the best for the purpose for many reasons, the principal ones of which are the greater facility in turning without cramping the connections and the adaptability to be constructed with dumping bodies or beds.

The wheels of all the trucks are of the usual character of traction-wheels, and the trucks are coupled together by any suitable connections, such as are shown by E, permitting each to have its necessary independence of movement.

On the leading truck A is mounted a steam boiler, a, an engine, a', supplied by the boiler and having a driving-shaft, a², from which power is transmitted to the crank-shaft a³, the ends of which carry pinions a⁴, meshing with annular gears a⁵, secured to the truck-wheels. Any other arrangement of the power mechanism may be used, the object being to transmit enough power to propel the truck A. The object now is to furnish a portion of the original power directly, and not through traction, to the succeeding trucks. There may be several ways of accomplishing this. I have herein illustrated two, namely: Upon the truck B it will be seen I locate two engines, consisting of steam-cylinders b, provided with the usual steam-ports, valve-chest, pistons, &c., and having pitmen b' connected with a crank-shaft, b², the ends of which carry pinions b³, meshing with annular gears b⁴ on the truck-wheels.

A steam-pipe, F, leads from the boiler on truck A to these cylinders b, whereby steam is furnished for their operation, and in this way the truck B is propelled by its own machinery, operated by power transmitted directly from the source of power on the leading truck. The leading truck does not, therefore, act as a traction-engine, except to propel itself. It draws no load, for the succeeding trucks follow, not by traction from the first, but of

themselves. These means for conveying the original motive force direct may be employed throughout all the members of the train; and at present I deem them preferable to any others; but instead of thus conducting the steam from the boiler to each truck by means of a pipe suitably coupled in sections I may use the power-transmitting mechanism shown between the trucks C and D. Here an endless belt, G, passes around pulleys c d on shafts c' d' under the trucks, said shafts carrying pinions c² d², meshing with annular gears c³ d³ on the truck-wheels. A vertically-adjustable gravity pulley, f, keeps the belt taut while it is conducted in a straight line to its pulleys, no matter at what angle the trucks may stand with relation to each other, by the vertically-arranged guide-rollers c⁴ d⁴ on the adjacent ends of the trucks. When such means as these are used for transmitting the power, the engine upon the leading truck will, of course, be made powerful enough for the purpose.

The pinions which mesh with the wheel-gears may be affected by clutches to throw them into and out of gear with the shafts upon which they are mounted, thus providing for the discontinuance of the operation of any member of the train.

Having thus described my invention, what I claim as new, and desire to secure by Letters Patent, is—

1. In a wagon-train the members of which are suitably coupled, independent propelling-engines upon each member of the train and connected with the driving-wheels, and a steam-boiler upon the leading member of the train, connected with and operating the engine on the succeeding members, substantially as and for the purpose herein described.

2. In a wagon-train the members of which are suitably coupled, independent gearing upon each member of the train, by which its drive-wheels are operated, in combination with a steam-boiler on the leading member of the train, steam-engines upon each member of the train and connected with the gearing thereof, and suitable steam-pipes, by which the steam from the boiler is conveyed to the engines of each member of the train, substantially as described.

In witness whereof I have hereunto set my hand.

JONAS B. OSBORNE.
